Diagram illustrating a hexagonal structure with internal features and labeled vertices. The vertices are labeled with lowercase letters: *e*, *v*, *f*, *i*, *a*, *h*, *b*, *d*, *c*, *i*, *g*, and *e*. The structure appears to be a hexagonal prism with a central hexagonal cavity and various internal features.

UNITED STATES PATENT OFFICE.

ROBERT L. LYONS, OF WALTHAM, MASSACHUSETTS, ASSIGNOR TO THE FREDERICK OSANN COMPANY, OF NEW YORK, N. Y., A CORPORATION OF NEW YORK.

SEWING-MACHINE.

1,272,067.

Specification of Letters Patent. Patented July 9, 1918.

Application filed July 24, 1914. Serial No. 852,782.

To all whom it may concern:

Be it known that I, ROBERT L. LYONS, a citizen of the United States, residing at Waltham, in the county of Middlesex and 5 State of Massachusetts, have invented new and useful Improvements in Sewing-Machines, of which the following is a specification, reference being had to the accompanying drawings, forming part thereof.

10 This invention has reference to an improved sewing machine for sewing on snap fasteners and other similar devices having axes around which are arranged in symmetrical order means to be attached to material 15 by stitches.

One object of the invention is to sew by machine, fastening devices ordinarily known as snap fasteners so that the groups of sewing stitches may extend beyond the 20 periphery of the fastener and the crossing thread or threads between such stitches need not interfere with the operation of the fastener.

Another object of the invention is to sew 25 by machine, fasteners of the general nature referred to so that the groups of stitches may extend approximately radially and that the crossing from one group of stitches to another extends outside the periphery of 30 the fastener.

Another object of the invention is to sew by machine, fasteners of the general nature referred to and having needle passages that 35 stitches from all of said passages may be sewn to extend beyond the periphery of the fastener as a succession of steps in one complete sewing operation or cycle without arresting the operation of the machine.

Another object of the invention is to improve 40 the construction of sewing machines particularly with reference to the construction of the work sustaining and holding devices.

Other objects of the invention will appear 45 from the following description.

The invention consists in the improved method of sewing on fasteners of the nature described.

The invention also consists in the manner 50 of sustaining and operating the work relative to the needle.

The invention also consists in such novel features of construction and combination of parts as shall hereinafter be more fully described and pointed out in the claims. 55

Figure 1, represents a side view of the improved sewing machine, parts of the same being broken away.

Fig. 2, represents a sectional plan view of the same taken on line 2—2 Fig. 1. 60

Figs. 3 and 4, represent side views of portions of the improved presser foot or holder.

Fig. 5, represents a plan view of the same.

Fig. 6, represents a plan view of a fastener member attached to a piece of fabric 65 by the new method.

Fig. 7, represents an enlarged plan view of parts of the machine to show details of parts by which the work holder is caused to vibrate. 70

Fig. 8, represents a sectional view taken on line 8—8 Fig. 7.

Fig. 9, represents a similar view taken on line 9—9 Fig. 7 and, in addition, showing a sectional view of parts of the completed 75 work.

Similar reference characters designate corresponding parts throughout.

Fasteners of the nature herein referred to usually comprise a pair of disks or bases furnished with complementary engaging devices of some kind which define axes of symmetry around which are arranged perforations, openings or needle passages through which a needle may pass in the operation of sewing 80

said disks or bases to parts of garments or to other articles adapted to be temporarily secured together by the engagement of the respective engaging devices of said fasteners. As such engaging devices 85

are generally located at or near the center of said disks or bases the manner of separating the same is to exert a separating strain on the edges or peripheries of said disks and sometimes this may be accomplished by 90

pulling apart the fabric to which said bases are attached and this operation is best accomplished if the edges or peripheries of the fastener members or disks are secured to the fabric as it is evident that such separation 95 is facilitated by the leverage of the disks at their diameters and that the pull of the stitches, in the separating movement of the parts to which the fasteners are attached, should be exerted as near as possible to the 100 greatest diameters of the fastener members.

Usually the perforations or needle passages of the fastener members are furnished out of the sheet metal of said members so that said perforations have sharp edges 110

which are liable to cut the thread if a group of stitches is sewn through two of said perforations and drawn tight, while if the group of stitches is sewn through but one of 5 said perforations and extends over the raised edge of the fastener member said stitches are not necessarily drawn tight against the raw or sharp edge of the perforation. It is also desirable to avoid placing stitches or crossing threads between groups of stitches across 10 the spring arms or other devices of the fasteners as the presence of such stitches tends to hold said devices from operation.

As shown in the drawings in its preferred 15 form 10 indicates the bed of the machine having the usual frame 11 having the arm 12 and the head 13 which latter is furnished with a guide, of any well known construction, for the needle bar 14 which needle bar 20 is operated in any usual manner. The bed 10 at its forward end has the needle passage 15, Fig. 2, and has also the depending shafts 16 and 17 on which respectively are 25 rotatably mounted the cams 18 and 19 furnished with the gears 20 and 21 driven from the gears 22 and 23 of the main shaft 24. This latter shaft is journaled in bearings beneath or within the bed 10 and drives the looper 25 in any known manner. Also de- 30 pending from the bed 10 are the bearings 26 and 27 in which are journaled the follower shafts 28 and 29 having at their lower ends the follower arms 30 and 31 respectively having followers which are engaged 35 with the grooves or channels of their related cams 18 and 19.

The work carriage, indicated as a whole by character 32 is mounted for longitudinal and sidewise movement on the bed 10 and 40 is connected by means of adjustable members 33, 33' and 33² with the follower shaft 28 whereby the vibratory movement of the follower of arm 30, effected by cam 18 is transmitted to said work carriage to move 45 said carriage back and forth longitudinally and at times to arrest such movement or to permit the carriage to dwell in such movement while cam 19 acts on its related follower to actuate follower arm 31 and shaft 29 to effect 50 lateral movement of the work carriage 32 by means of the adjustable members 34 by which said shaft 29 and said carriage are connected, such lateral movement of carriage 32 in one direction being assisted by 55 spring 35 attached to a portion of said carriage and to a fixed part of the machine.

Carriage 32 has the forwardly extending work supporting plate 36 having the opening or needle passage 37 into which extends 60 the tongue 38 having the enlarged end 39, which approximately defines the axis of the opening 37. The shape and dimensions of the needle passage 37 between its edge and the edge of tongue 38 and its end 39 are such 65 that it will clear the path of the needle in

the various movements of carriage 32 to permit the passage of the needle in the sewing of the several groups of attaching stitches and the tongue 38 is made narrow to clear the needle in its movement in making the 70 first group of sewing stitches and the last of the series of groups of such stitches.

Carriage 32 is also provided with the pivoted arm 40 having means at its free end for receiving and holding the presser and holder member 41 or 42 as the case may be. Member 41 has the centering stud 43 which is adapted to be received in a central opening usually found in one of a pair of snap fastener members and spaced from said stud 80 is the holding pin 44 adapted to engage with a notch or other means with which the fastener members are provided as will hereafter be more fully described. Member 42 is similar in all respects to member 41 except that the stud 43 of member 42 is displaced by the concavity 45 to engage with the centrally disposed head of a fastener member as is indicated in Fig. 3. I have however found that the stud 43 of member 41 may be supplied with a concavity similar to 45 of sufficient size to accomplish the centering and, with the assistance of the pin 44, the holding of a fastening member having a suitable head. 95

Provision is made for lifting the free end of the pivoted arm 40 to release the presser and holder member 41 or 42, as the case may be, from the work, and such provision comprises the rock shaft 46 mounted in bearings of the machine arm 12 and having levers of which 48 is connected by the chain 49 and the adjustable member 50 with a member of the pivoted arm 40 of said carriage. 100

One of the fastener members adapted to be attached by the improved method is shown in Fig. 3 in side view and in Fig. 6 in plan view as attached by sewing stitches. It is to be understood however that this showing is more particularly for the purpose of illustrating the operation of the improved machine. 110

As shown in said Figs. 3 and 6 the fastener member comprises the disk *a* usually 115 of sheet metal and having the central stud or head *b* and the raised edge *c* furnished with the peripheral notch or engagement *d* and, adjacent said raised edge *c*, the disk *a* has the series of perforations *e*, *f*, *f* and *g*, the perforation *e* being the perforation through which portions of the initial group of attaching stitches are sewn and *g* the perforation adapted to receive portions of the final group of stitches, the notch *d* being located between the initial and final sewing operations. The stud *b* or any similarly located member approximately defines the axis of the fastener with respect to the symmetrical arrangement about said axis of the 120 130

perforations *e*, *f*, *f* and *g*, and with reference to which axis it is preferred to extend the sewing stitches radially from said perforations to points on the work outside the 5 edge *c*.

In preparing for the operation of the machine the arm 40 of the work carriage, with its presser, in the present instance 42, is raised and a piece of fabric *h* is placed on 10 the work supporting plate 36 covering the needle passage 37. One of the fastener members is placed on said fabric *h* and the arm 40 with its presser 42 is permitted to descend while the fastener member is adjusted to bring its head or stud into registry 15 with the concavity 45 and its notch *d* in position to receive the holding pin 44. The engagement of these parts will effect the holding or retaining of the fastener 20 member at two points within its periphery and is for the purpose of preventing rotation of the fastener during the sewing operation, and also for the purpose of positioning the perforation *e* of the fastener 25 receive the needle in the operation of sewing the first group of attaching stitches.

Presumably the machine is supplied with needle and thread and is otherwise in condition for sewing. When the machine is started 30 the first group of stitches is sewn approximately radially of the axis of the fastener, that is through the perforation *e* and outward to a point on the fabric *h* and such group of stitches is completed at 35 said point so that when the fastener members are moved, by the operation of cams 18, 19 and the parts for transmitting motion therefrom to the work holder, to bring one of the perforations *f*, *f* of the fastener in 40 position to receive the needle in sewing the next group of stitches the crossing threads *i*, *i* will extend outside the periphery of the fastener. The successive positioning movements of the work, and of course the 45 vibratory movement thereof to sew the stitches over the edge *c* of the fastener member, is continued until groups of stitches have been formed through the required number of perforations *f*, *f* and the last group 50 of stitches is sewn through perforation *g* of said fastener after which the work is removed from the machine or is moved along to bring another part of the fabric into position beneath the presser and holding member. 55

The fastener member complementary to that shown in Figs. 3 and 6 of the drawing is also provided with the perforations *e*, *f*, *f*, and *g* and with the notch *d* extending inward from its periphery.

It is of course to be understood that this invention is not limited to the particular work holder or to the means for effecting relative movement between the work and 65 the needle, for instance, this may be ac-

complished by the well known expedient of slidably mounting the needle bar in a guide and effecting the lateral movement of said guide.

While I prefer to have all of the crossing 70 threads outside the periphery of the fastener member I understand that said crossing threads may extend from the outer end of one group of stitches diagonally to the inner end of the next group of stitches or 75 said crossing threads may extend between the inner ends of the several groups of stitches without departing from the spirit of my invention.

Having thus described my invention I 80 claim as new and desire to secure by Letters Patent.

1. A sewing machine comprising stitch forming means, a work holder movably mounted, and means for effecting relative 85 lateral periodic positioning movement in two directions between said work holder and said stitch forming devices, for arresting said movement at times and for effecting relative stitch forming vibrations at the 90 times at which said positioning movements are arrested.

2. A sewing machine comprising stitch forming devices, a work holder movably mounted, and means for effecting relative 95 positioning movement in two lateral directions between said work holder and said stitch forming devices to position several points around a common axis in registry with said stitch forming devices, and for 100 changing said positioning movement to vibratory stitch forming movements at each of said points.

3. A sewing machine comprising stitch forming means, a work holder for work having an axis of symmetry, and means for effecting relative lateral positioning movements in two directions between said work holder and said stitch forming devices to position the work in registry with the 105 needle at several points around the axis of symmetry of the work and for changing such positioning movement to lateral stitch forming vibrations radially with respect to said axis at each of said points of registry. 110

4. A sewing machine comprising stitch forming means, a work holder for work having an axis of symmetry, and means for moving said work holder in two lateral directions relative to such stitch forming devices and 115 for changing said lateral movement of the work holder at predetermined points to a vibratory stitch forming movement in directions radial of said axis.

5. A sewing machine comprising a work 125 holder for a snap fastener member and material, said work holder having complementary means for engaging said member and material, stitch forming means, and mechanism to effect relative lateral positioning move- 130

ments between said work holder and said stitch forming means to position the work in registry with said stitch forming means successively at several points related to the 5 periphery of said member and for changing said positioning movement at each of said points of registry to a vibratory movement to form stitches extending from points within the margin of said fastener member to 10 points outside said margin.

6. A sewing machine comprising stitch forming means, a work holder for work having an axis of symmetry movably mounted and having means for sustaining work 15 horizontally, and a presser defining the median line of the work, and means for moving said work holder laterally and longitudinally of said presser and for changing said movement of the work holder at times 20 to a vibratory stitch forming movement whereby groups of stitches extending radi-

ally of said axis may be formed at both sides of said presser.

7. A sewing machine comprising stitch forming means, a work holder furnished 25 with a work sustaining plate having a needle passage and a tongue extending to the axis of said passage, and a work centering means coöperating solely with the end of said tongue. 30

8. A sewing machine comprising stitch forming means, a work holder furnished with a work sustaining plate having a needle passage and a tongue extending to the axis of said passage, and a presser member piv- 35 otally mounted on said work holder and having work centering means coöperating solely with the end of said tongue.
